(57) **CLAIM**

The ornamental design for an induction charging device, as shown and described.

DESCRIPTION

FIG. 1 is a perspective view for an embodiment of an induction charging device;

FIG. 2 is a front elevation view thereof;

FIG. 3 is a back elevation view thereof;

FIG. 4 is a left elevation view thereof;

FIG. 5 is a right elevation view thereof;

FIG. 6 is a top elevation view thereof; and,

FIG. 7 is a bottom elevation view thereof.

Any dashed lines in the drawings illustrate portions of the induction charging device that form no part of the claimed design.

The surface shading and contour lines (including any CAD or wire frame lines) in the drawings is a drawing convention to represent character and contour; it does not illustrate material, surface ornamentalations, or surface decoration and forms no part of the claimed design.
